(57) **CLAIM**

The ornamental design for a compact ergonomic computer mouse, as shown and described.

DESCRIPTION

FIG. 1 is a left rear perspective view of a compact ergonomic computer mouse showing my new design.

FIG. 2 is a right rear perspective view thereof.

FIG. 3 is a left view thereof.

FIG. 4 is a right view thereof.

FIG. 5 is a front view thereof.

FIG. 6 is a rear view thereof.

FIG. 7 is a top view thereof; and,

FIG. 8 is a bottom view thereof.

The broken lines which define the bounds of the claimed design form no part thereof.
